GUNTHER JOBST AND HANS RODER, OF BERLIN, GERMANY, ASSIGNORS TO GESELLSCHAFT FÜR DRAHTLOSE TELEGRAPHIE M. B. H. HALLESCHES, OF BERLIN, GERMANY, A CORPORATION OF GERMANY

DOUBLE-GRID-TUBE TRANSMITTER

Application filed February 6, 1928, Serial No. 252,182, and in Germany February 26, 1927.

The subject matter of the present invention is an arrangement for telephony and telegraphy circuits for valve or tube transmitters.

It is well known that modulation of electric waves may be effected in a self excited or a separately excited double grid tube, by impressing modulating potentials upon the anode screening grid.

In the circuit arrangements heretofore most commonly used, the inconvenience is often met that during the periods when this grid is subject to the action of positive potential, disturbing influences of the secondary electron current issuing from the space charge grid manifest themselves, and that furthermore a grid current flows in the circuit of the protective grid.

According to the disclosures of the present invention, an arrangement is used in which this objectionable feature is eliminated by maintaining the total potential at the anode screening grid always negative during the transmission of signals. One method of arriving at this result is to use only the negative half cycles of the oscillations used for the transmission of signals. A more practical scheme is to apply a negative biasing potential to the anode screening grid, the value of said biasing potential being chosen a great enough value so that the total potential will remain permanently negative.

An arrangement according to the present invention is illustrated in the drawings in which Fig. 1 represents one preferred embodiment of our invention, and

Fig. 2, shows curves explaining the condition of the circuit shown in Fig. 1.

As will be seen from Fig. 1, a thermionic tube comprising an incandescent filament 1, space charge grid 2, protective (screening) grid 3 and a plate 4 is subject to separate excitation from a generator 5, while the anode screening grid is influenced from a telephone 45. Inserted in this grid circuit is a battery

7 whose potential is so chosen that the total resulting potential at the grid 3 remains always negative.

The shape of the potential at the grid 3 is shown in Fig. 2 by curve 8. The total potential at any instant, consists of the potential $-E_7$ of the battery 7, plus the instantaneous impressed alternating current potential of the generator 5. As will be seen from the graph, the size of the battery potential must be so selected that it will be higher than the greatest amplitude E_5 of the alternating current potential so that no possibility of the grid ever becoming positive will occur.

In Fig. 2, curve 9 shows the impressed voltage due to the generator 5, while the line 10 shows the battery 7 negative potential upon the grid 4. Adding these two curves algebraically, curve 8 will be obtained from which the true condition of the grid will be evident.

While we have indicated and described one arrangement for carrying our invention into effect, it will be apparent to one skilled in the art that our invention is by no means limited to the particular organization shown and described, but that many modifications may be employed without departing from the scope of our invention as set forth in the appended claims.

Having thus described our invention, what we desire to protect by Letters Patent is as follows:

1. In a transmitter circuit, a double grid tube circuit comprising a space charge grid circuit and an anode screening grid circuit, means comprising a source of high frequency currents and a condenser, in series with said space charge grid and conductively associated therewith for generating oscillations in said transmitter, modulating means for said anode screening grid, and means for maintaining the total potential at said last named grid at a negative value.

2. A transmitter circuit comprising a dou-
